Primary Examiner — Susan Moon Lee(74) *Attorney, Agent, or Firm* — Duane Morris LLP**CLAIM**

We claim the ornamental design for a coded information reader, as shown and described.

DESCRIPTION

FIG. 1 is a perspective front view of a coded information reader according to the present invention.

FIG. 2 is a front elevation view of the coded information reader of FIG. 1.

FIG. 3 is a rear elevation view of the coded information reader of FIG. 1.

FIG. 4 is a top view of the coded information reader of FIG. 1.

FIG. 5 is a right side elevation view of the coded information reader of FIG. 1; and,

FIG. 6 is a left side elevation view of the coded information reader of FIG. 1.

The bottom of the coded information reader of FIG. 1 is flat and devoid of surface ornamentation.

Broken lines and unshaded portions contained within broken lines are not claimed.

1 Claim, 6 Drawing Sheets(56)
